(57) **CLAIM**

I claim the ornamental design of a battery access door for electronic mortise door lock, as shown and described.

DESCRIPTION

FIG. 1 is a perspective view of a door that includes an electronic mortise door lock situated above a battery access door for accessing batteries that power the electronic mortise door lock.

FIG. 2 is a perspective view of the door of FIG. 1 with the battery access door in a partially open position.

FIG. 3 is a perspective view of a front of the battery access door of FIG. 1.

FIG. 4 is a perspective view of a rear of the battery access door of FIG. 1.

FIG. 5 is a view of the front of the battery access door of FIG. 1.

FIG. 6 is a view of the rear of the battery access door of FIG. 1 that is opposite the view of FIG. 5.

FIG. 7 is a side view of the battery access door taken from a first side; and,

FIG. 8 is a side view of the battery access door taken from a second side that is opposite the first side of FIG. 7.

The broken lines in the figures show portions of the battery access door that form no part of the claimed design.
